UNITED STATES PATENT OFFICE.

GEORGE HENRY SARGENT, RICHARD HENRY COUPE, AND BENJAMIN WALKER, OF BINGLEY, ENGLAND.

LOOM FOR WEAVING LOOPED-PILE FABRICS.

SPECIFICATION forming part of Letters Patent No. 610,563, dated September 13, 1898.

Application filed September 3, 1896. Serial No. 604,695. (No model.)

To all whom it may concern:

Be it known that we, GEORGE HENRY SARGENT, RICHARD HENRY COUPE, and BENJAMIN WALKER, subjects of the Queen of England, residing at Bingley, in the county of York, England, have invented certain new and useful Improvements in Looms for Weaving Looped-Pile Fabrics, of which the following is a specification.

This invention relates to improvements in that type of loom for weaving looped-pile fabrics in which the loops are formed by a hooked comb or a series of hooks engaging the pile-warp. In the accompanying drawings, forming a part of this specification, Figure 1 represents a front elevation of such parts of a loom as are necessary to illustrate the application of our improvements. Fig. 2 represents an end view, and Fig. 3 a plan view, of the same. Figs. 4 and 5 are views of details hereinafter referred to.

The hooked comb A is mounted on curved arms A² and A³ and A⁸, projecting from the 25 rocking shaft A⁴, mounted in bearings A⁵, formed in the brackets B and B', fixed to the front rail A⁸. The bracket B is continued beyond shaft A⁴, and its inner end is secured to the side frame B². The arm A² has an 30 tension A' at the back, connected by the rod C to the crank-pin C² of the crank C³, fixed on the inner end of the short shaft C⁴, mounted in the bearings B⁴, formed in the side frame B². The short shaft C⁴ is intermittently operated by the wheel C⁵, fixed on the tappet-shaft H³, engaging the wheel C⁶, loosely mounted on the short shaft C⁴, and this latter wheel is locked to the short shaft by means of the sliding clutch C⁷, the jaws C⁸ of which 35 are made to engage the jaws C⁹, cast on the face of the wheel C⁶. The clutch is normally held disengaged from the wheel C⁶ by the spring D, stretched between the stud D² on the bracket D³, (shown partly broken away,) 40 fixed to the side frame B², and the arm or lever D⁴, projecting from the top of the pivot D' of the clutch-lever D⁶. The pivot D' is rigidly secured to the lever D⁶ and is mounted in a vertical bearing D⁷, formed in the bracket D⁸. The lever D⁶ has a piece D⁸ 45 hinged to its rear end, and this piece D⁸ is

provided with a stud D⁹, adapted to engage the cam-race E, formed in the periphery of the cam E², secured on the tappet-shaft H³. The stud D⁹ is normally held up clear of the race E by means of the rod E³, connecting the piece D⁸ to the bell-crank lever E⁴, pivoted on the top cross-rail A⁶, and this bell-crank lever is also connected by the rod E⁵ to one of the jack-levers E⁶ of a dobby, which latter it has not been deemed necessary to show in the drawings, as its construction and operation are well known; but when the comb requires to be operated to engage the pile-warp the jack-lever E⁶ of the dobby is arranged to be operated and thereby lower the piece D⁸, which allows the stud D⁹ thereon to engage the cam-race E. As soon as the stud engages the cam-race the lever D⁶ is thereby operated so as to throw the clutch into gear with the wheel C⁶ and the shaft C⁴ is rotated until the jack-lever returns to its normal position and releases the cam-stud D⁹ from the cam-race E. The wheels C⁵ and C⁶ are each provided with a thick strong tooth e, 75 which are arranged to be engaging each other just as the cam throws the clutch into gear and are provided to withstand the extra strain or jerk of suddenly starting the shaft C⁴. The rotation of the shaft C⁴ also imparts a longitudinal movement to the shaft A⁴. This is effected by means of the fork F, having 80 projections F², engaging the annular groove F³, formed in the collar F⁴, fixed on the shaft A⁴. The fork F is mounted on the cross-shaft F⁵, mounted in brackets F⁶ and F⁷, respectively secured to the top bracket B. The shaft F⁵ is rocked or operated as required by means of the cam or eccentric C' on the shortshaft C⁴, engaging the antifriction-roller F⁶, carried by the arm F⁷, mounted on the stud B⁶, fixed on the side frame B², and the arm F⁷ is connected by the rod F⁸ to the arm F⁹, rigidly secured to the shaft F⁵.

The pile-warp is mounted on the warp-beams G and G² and is let off by means of the let-off rollers G³ and G⁴, operated by the ratchet-wheels G⁵ and G⁶, secured to them and actuated by the pawls G⁷ and G⁸, respectively pivoted on the levers H and H², loosely mounted on the arbors G⁹ of the rollers G³ and G⁴. The levers H and H² are vibrated by the jack-

levers E⁷ and E⁸, Fig. 3, of the dobby and are connected thereto by the rods H⁴ H⁴, the bell-crank levers H⁵ H⁵, and rods H⁶ H⁶.

It is generally desirable to miss a pick while the looping mechanism is in operation. For this purpose the loom may be arranged at suitable intervals to miss a pick at one end and make two picks in succession at the other end, the second pick being made when the shuttle is in the opposite shuttle-box. For this purpose the cone or antifriction-roller K² on each of the picking-shafts K³ is carried by a collar K⁴, loosely mounted on said shaft. This collar is connected to the collar K⁵, rigidly fixed below to the shaft by means of the sliding key-piece K⁶, having two projecting keys K⁷ K⁷, fitting grooves formed in the periphery of the collar K⁴, and the ends of said keys project into notches formed in the upper face of the collar K⁵. Fig. 5 represents a separate sectional view of these parts. To disconnect the picking-shafts from the collars K⁴, the lever L is provided at one side and the lever L² at the other. These levers are each pivoted upon the lower cross-rail K⁸ and are provided with forked ends L³, engaging grooves K⁹ formed in the said key-pieces. The levers L and L² are connected together by means of the rod L'. The lever L is connected by the rod L⁴ to the lever L⁵, pivoted to the bottom cross-rail K⁸, and its free end is connected by the rod L⁶ to the lever L⁷, mounted on the stud L⁸, projecting from the side frame B³. These parts are clearly shown in Fig. 4, which represents an elevation of a portion of the opposite side of the loom to that shown in Fig. 2. The lever L⁷ is provided with an arm L⁹, which bears upon the peg-cylinder M or equivalent device. The lever L² is held by the spring M² in the position shown and the keys K⁷ are disengaged from the collar; but the pegs in the cylinder M are so arranged that each time a pick is required to be made at this end of the loom the arm L⁹ is raised, which through the medium of the connecting mechanism operates the levers L and L², thereby disconnecting the picking-cone K² on the right-hand side of the loom and connecting the one on the left-hand side with the picking-shaft, and while they remain thus a pick will not be made on the right-hand side of the loom. On the other hand, a pick is only made at the left-hand side when the cone on the right hand is disconnected from the picking-shaft. The cylinder M is driven in a similar way to the cylinder operating the "drop-box" mechanism

of a "drop-box" loom or in any other convenient manner.

To prevent the weft-fork mechanism from operating the stop mechanism when a pick is missed in this way, we provide a projection N on the spindle N², carrying the weft-fork N³, which projection is engaged by the top of the rod O each time a pick is missed, and the weft-fork is thereby prevented from falling and putting the stop mechanism into operation.

The rod O passes through the top guide O², secured to the front of the slay O³, and is hinged below to the arm O⁴, projecting from the front of the rocking shaft O⁵, mounted in bearings O⁶ O⁶. The shaft O⁵ is vibrated each time the comb A is operated by its arm O⁷, connected to the arm O⁸ by the rod O⁹. The arm O⁸ carries an antifriction-roller R, which is kept in contact with the periphery of the cam R² (rigidly secured to the boss of the wheel C⁶) by the spiral spring S.

The comb and the mechanism for operating the same are not claimed herein, the same forming the subject of a separate application of even date, designated by Serial No. 604,694.

We claim—

1. In a loom for weaving looped-pile fabrics, the combination with pile-forming mechanism and the weft stop-fork and its spindle, of means controlled by the pile-forming mechanism for holding the weft-fork out of action when a pick requires to be missed comprising a projection on the weft-fork spindle, a rod adapted to engage said projection when a pick is missed and hold the fork out of operation, and a vibrating shaft with which said rod has a jointed connection, adapted to be vibrated each time the comb of the pile-forming mechanism is operated.

2. In a loom for weaving looped-pile fabrics, the combination with the weft stop-fork, of the pile-forming mechanism, a device adapted to hold the weft-fork out of action when a pick requires to be missed, and connections between the said device and the pile-forming mechanism whereby the latter controls the said device, as described.

In testimony whereof we have hereunto set our hands in the presence of the two subscribing witnesses.
